UNITED STATES PATENT OFFICE.

HARRY GAITHER, OF MONUMENT, NEW MEXICO.

WINDMILL.

Application filed July 25, 1921. Serial No. 487,294.

To all whom it may concern:

Be it known that I, HARRY GAITHER, a citizen of the United States, residing at Monument, in the county of Lea and State 5 of New Mexico, have invented certain new and useful Improvements in a Windmill, of which the following is a specification.

This invention relates to a windmill and has for its principal object to generally 10 prove upon devices of this character by providing a mechanism which will be of extremely simple and efficient construction and well adapted to the purpose for which it is designed.

Another object of the invention is to 15 construct a windmill which is capable of revolving so as to place its propellers in proper position so that they will come into efficient engagement with the wind.

In order that those skilled in this art may have a full understanding of the invention, I have illustrated a desirable and preferred embodiment of the same in the accompanying drawing forming a part of this specification, and throughout the various views of 20 which like reference numerals refer to the same parts.

In the drawing:

Figure 1 is an elevational view of the 25 windmill, and

Figure 2 is a central longitudinally vertically arranged sectional view.

Referring to the drawing in detail it will be seen that 1 designates a base in which is 30 mounted a tube 2. A platform 3 is revolvably mounted upon the base 1 by means of the castors 4 or any other suitable means and the tube 2 passes therethrough as is shown to advantage in Figure 2.

A plurality of standards 5 extends upwardly from the platform 3 and in the present illustrations these standards are four in 35 number and are equally spaced from each other. The shafts 6 and 7 are suitably journaled in the standards 5 and have keyed thereto intermediate their ends the propellers indicated generally by the numeral 8. Each propeller consists of a plurality of pins or blades 9 radiating from the hub 10 and a pair of rings 11 are connected to each of the blades 9 upon each side thereof and flexible members 12 are connected at one end to the rings 11 and at the other end to the collars 13 which are suitably fixed to the shafts 6 and 7 adjacent their ends. Thus 55 it will be seen that a propeller has been pro-

vided which is efficiently braced and will be capable of operation in the stronger currents of the air.

Suitable beveled gears 14 are situated on 60 the terminals of the shafts 6 and 7 and are in mesh with the beveled gears 15 mounted on the shaft 16 which is suitably journaled so as to extend longitudinally of the standards 5 and is journaled in the brackets 17. 65 In the present illustration there are two of these shafts 16 to accommodate the four propellers shown but of course any number of these propellers might be used depending upon their size and the height of the standards 5. At the lower end of the shaft 16 there are situated the beveled gears 18 which are in mesh with the beveled gears 19 on the crank shaft 20. A connecting rod 21 is in engagement with the crank pin of the crank 70 shaft 20 and is pivoted at its other end to a rod 22 slidably mounted in the tube 2 and brace rods 23. This rod upon rotation of the propellers 8 will have a reciprocating motion which may be used for any desired purposes. 75

The upper ends of the standards 5 are connected by the cross beams 25 and are provided with converging extensions 26 which are suitably connected by a bracket 27 in 80 which is swivelly mounted an eye bolt 29 to which are attached the plurality of wires or cables 30. These cables are drawn taut and fastened to any suitable anchoring means thus efficiently bracing the top of the windmill. 90

Having thus described my invention what I claim as new is:

1. In combination, a base, a platform revolvably mounted on the base, a frame 95 mounted on the platform and including a plurality of upright standards, extensions mounted on the standards of the frame and disposed so as to converge toward each other, a bracket for receiving the terminals of the extensions, an eye bolt swivelly mounted in the bracket, and means for bracing the eye bolt, and a propeller mounted on the frame in the manner and for the purpose specified.

2. In combination, a base, a platform 100 revolvably mounted on the base, a tube extending through the base and projecting centrally through the platform to act as an axle therefor, a rod reciprocatable through the tube, and wind propulsion means mounted 105 on the platform for reciprocating the rod.

3. In combination, a base, a platform re-

revolvably mounted on the base, a plurality of upright standards mounted on the platform to form a frame, a shaft journaled between two of the upright standards, wind propulsive means on the shaft, a second shaft journaled on one standard so as to extend longitudinally therewith in parallelism and adjacent thereto, gears disposed between the two shafts, and power transmitting mechanism operable by the second mentioned shaft.

4. In combination, a base, a platform revolvably mounted on the base, a frame mounted on the base and including a plurality of upstanding standards, extensions mounted on the standards of the frame at the upper ends thereof and disposed so as to converge toward each other, a bracket for receiving the terminals of the extensions, an

eye bolt swivelly mounted in the bracket, means for bracing the eye bolt, a shaft journaled between two of the standards, a propeller mounted on the shaft, a second shaft, journaled longitudinally with and in parallelism with one standard, a tube extending through the base and the platform to act as an axle for the platform, a shaft reciprocatable through the tube, and means for reciprocating the rod, said means being operable by the second mentioned shaft.

In testimony whereof I affix my signature in presence of two witnesses.

HARRY GAITHER.
